MATERIAL PACKAGING

Nels H. Petersen, Racine, Wis., assignor to Addison-Semmes Corporation, Racine, Wis., a corporation of Wisconsin

Application May 7, 1948, Serial No. 25,749

14 Claims. (Cl. 206—62)

1

This invention relates to the packaging of materials, and has to do with a package for handling and shipping articles, particularly articles which are fragile or frangible in character.

The breakage in handling and shipping articles composed in substantial part of glass or other frangible or fragile material, under present conditions of packaging such articles, is quite high and the freight rate in shipping such articles is also high. The present practice in packaging articles formed to substantial extent of glass, such as window units, for example, is to place the article within a frame formed of lumber, with a thick filling of straw or similar material at opposite sides of the article, the sides of the frame being then closed by wooden slats or boards nailed to the frame; the whole constituting a crate of substantial weight. This method of packing the article for shipment is time consuming and the packaged article is excessively heavy, rendering it difficult to handle, particularly if the article itself is of substantial weight, with the attendant risk of breakage of the article in shipment, or in handling, due to falling or dropping of the crate with the article therein. A further objection to the present method of packaging above referred to is that the packaged or crated article is excessively heavy, as above noted, and a substantial portion of the freight charge is paid for the crate and the packaging or cushioning material therein rather than on the article itself. The time required to package the article and the weight of the packaged or crated article are important considerations in respect to the cost of shipping the crated article and the likelihood of breakage, as will be clear.

My invention is directed to means whereby the above noted objections to the present practice are substantially reduced. More particularly, I provide means whereby the packaging of articles is materially expedited, thereby effecting a substantial saving in time, risk of breakage of the packaged article is greatly reduced, and the weight of the packaged article is materially less than under the present practice above referred to, thereby facilitating handling of the packaged article, reducing likelihood of breakage due to falling or dropping of the packaged article and effecting a substantial saving in freight charges payable for shipment of the packaged article. Further objects and advantages of my invention will appear from the detail description.

In the drawings:

2

Figure 1 is a side view of a package embodying my invention;

Figure 2 is an end view of the package of Figure 1;

5 Figure 3 is a fragmentary vertical sectional view, on an enlarged scale, taken substantially on line 3—3 of Figure 1;

Figure 4 is an inner face view, on a reduced scale, of one of the pallets;

10 Figure 5 is a fragmentary inner face view, on an enlarged scale, of one of the pallets and of one of the spacer blocks thereof, showing in more detail the construction of the block;

15 Figure 6 is a view like Figure 1, but showing a modified form of package embodying my invention;

Figure 7 is a fragmentary vertical sectional view, on an enlarged scale, taken substantially on line 7—7 of Figure 6; and

20 Figure 8 is a side view, on a reduced scale, of the modified form of pallet used in Figures 6 and 7.

Window units comprising two panes of glass, spaced apart with a dead air space between them, 25 have come into rather extensive use. Such units, assembled at the factory, are shipped, after being packaged in the manner above described, to distributors or consumers. The package of my invention is particularly suitable for shipping window units of the character referred to and will be described as used for that purpose, by way of example, it being understood, however, that the package of my invention may be used for shipping various articles which, due to their 30 fragile or frangible character require care in packing, and shipping.

In Figures 1 to 5, inclusive, I have shown a package embodying my invention as used for handling and shipping an article 10, the particular article shown being a window unit of known construction comprising two panes of glass 11 suitably secured together with a spacer 12 between them, to provide a dead air space 13 between the panes 11. A thin metal frame 14, formed of aluminum, or any suitable metal, extends about the marginal portions of the panes 11 and the outer face of spacer 12, the parts being secured together by a suitable adhesive, as is known.

40 50 The unit 10, which is of rectangular shape in side view, is disposed within an open sided rectangular frame 15 formed of wooden rails 16 approximately four inches wide and one and a quarter inches thick, nailed together, as shown in Figure 1. The article 10 fits snugly within

frame 15 and preferably is positioned midway between the open sides thereof.

Two pallets 18 are disposed within frame 15, at opposite sides of the article 10. The pallets 18 are similar to the pallet of Patent No. 2,432,295, for Pallet, issued December 9, 1947, to William T. Donahue. Each of the pallets 18 comprises an outer deck 19 formed of two ply or double walled corrugated fiber board, paper board, or like material. Various materials, such as cardboard, paper board, chipboard and the like, classified generally as paper stock, and strawboard, which is analogous to but is not paper stock, may be used in the pallet 18. For convenience of description, I shall refer to the pallet as being formed of paper stock, that term being used in its generic sense and being inclusive of the various materials above mentioned and of equivalent materials. Accordingly, the term paper stock, as used both in the specification and the claims, is to be interpreted generally as has been indicated.

The pallet deck 19 has secured thereto, by means of a suitable adhesive, spacer members or blocks 20 preferably arranged in parallel rows 25 spaced apart transversely of deck 19, as shown in Figure 4. The respective blocks 20, preferably are each formed of a strip of corrugated paper stock, such as paper board or cardboard, wound spirally or convolutely into the form of an open cylinder, having a central opening of substantial extent, the convolutions of the block being adhesively secured together. The base 19 of pallet 18 substantially conforms to the interior of frame 15 and is effective as a closure for one side thereof. The blocks 20 are of such length that, when the pallet 18 is properly positioned within frame 15, their inner ends are in abutting relation to the corresponding side of the article 10. By abutting relation, I mean that the inner ends of the blocks 20 are disposed in close proximity to article 10, effective for restraining the latter against objectionable movement relative to frame 15 and toward the pallet 18.

Two pallets 18 are positioned within frame 15, at opposite sides of article 10, as shown in Figure 3. Preferably, a sheet of paper 22, or any suitable material, is disposed at each side of article 10, between the latter and the blocks 20 of the pallets, to protect the article against possible rubbing and scratching by the blocks 20, in the event that the inner end portions of the blocks should be coated or impregnated, to some extent, with the adhesive for securing the blocks to the base of the pallet, as may occur in some cases. When the article 10 and the pallets 18 are properly positioned within frame 15, the outer faces of the outer bases 19 of the pallets 18 are substantially flush with the side faces or surfaces of the frame 15. With the parts of the package properly assembled as above, the pallets 18 are restrained against movement outward of frame 15 by any suitable known means; preferably, by means of metal strapping secured about the frame 15 in a known manner, providing retaining steel bands 23 spaced a substantial distance apart, as shown in Figures 1 and 2. The bands 23 are applied under considerable tension and press into the wood of frame 15, particularly at the edges thereof, being thereby secured to the frame and anchored against relative movement. The outer bases 19 of the pallets 18 possess considerable resiliency, while being possessed also of substantial rigidity, and are capable of yield-

ing outward under pressure, thereby cushioning the article 10 and guarding against breakage thereof. Also, the corrugations of base 19 of the respective pallets 18 can be collapsed, in the event of excessive outward pressure being exerted thereon, such as might otherwise cause breakage of the article 10, thus providing cushioning means further guarding against breakage of article 10. Though the bands 23 are under substantial tension, the portions thereof extending across the frame 15 in overlying relation to the outer bases 19 of the pallets 18 are of substantial length and may be flexed outward of frame 15 under pressure. Accordingly, any outward movement of either of the pallets 18, relative to frame 15, is yieldingly restrained by the retaining bands 23 which, due to their inherent resiliency, serve as springs for cushioning such movement of the pallets. I thus take advantage of the inherent resiliency of the metal strapping or steel bands 23 for cushioning movement of the article 10 and the pallets 18 relative to frame 15, due to impact or other causes, thereby further reducing risk of breakage of the article 10.

The article 10 may be packaged with expedition and facility simply by laying the frame 15 on one side, upon a flat surface, inserting a pallet within the frame, then placing the article 10 within the frame, with the protective sheet 22 interposed between article 10 and the blocks 20 of the pallet, after which the other protective sheet 22 may be placed upon the article and the other pallet 18 placed within frame 15, the assembly being quickly secured together by means of the metal strapping 23. The frame 15, together with the parts therein, including the article 10 and the pallets 18, constitutes a complete package suitable for handling and shipment. This package effectively guards the article against breakage or damage, as above pointed out. In addition, the weight of the completed package is substantially less than the weight of a similar article packaged in accordance with the present practice above briefly described. For example, a window unit similar to article 10, measuring 66" x 96", and packaged or crated in accordance with the present practice above referred to, had a gross weight of 745 pounds. The same unit packaged in accordance with my invention had a gross weight of approximately 450 pounds. Test shipments have shown that units packaged in accordance with my invention are as effectively guarded against breakage or damage as units packaged or crated in accordance with the present practice and, in fact, indications are that packaging articles in accordance with my invention will effect a material saving in breakage. The substantial saving in weight, above referred to, is important since it effects a corresponding saving in shipping charges. Further, substantial reduction in weight of the packaged article renders it more easily handled and further reduces risk of breakage. A further advantage of packaging articles in accordance with my invention is that the time required for packaging is materially reduced compared with the present practice, thereby effecting a further substantial saving in cost.

In the modified form of package shown in Figures 6 and 7, the article 10a comprises the glass panes 11a secured together in spaced relation by a suitable adhesive material 12a which also serves as a spacer, the dead air space 13a between the panes 11a being of somewhat less thickness than the dead air space 13 shown in

Figure 3. The unit 10a is not provided with any marginal metal frame. In order to protect the edge portions of unit 10a, I provide a liner 24 fitting within the frame 15. The liner 24 is formed of double walled or two ply corrugated paper stock, such as cardboard, or paper board, or analogous material. Liner 24 is of channel cross section with its side flanges 25 disposed in lapping relation to the outer bases 19 of the pallets 18a, preferably seating on the outer faces of the bases 19. The channel liner 24 provides cushioning means protecting the edge portions of the unit 10a, and the flanges 25 of liner 24 provide cushion elements supplementing the pallet bases 19 and affording additional protection to the packaged article. When the steel strapping or bands 23 are drawn tightly about the frame 15, the corresponding areas of the flanges 25 of the liner 24 are crushed or flattened so that the bands 23 are effective for restraining the pallets 18a against outward movement relative to frame 15, as before.

Each of the pallets 18a is provided with an inner base 27, of single ply or single wall corrugated paper stock, corresponding to the outer base 19, the spacer blocks 20 being adhesively secured to inner base 27 as well as outer base 19. When using the two deck or base pallets 18a, the inner bases 27 thereof serve as protective sheets for the sides of the article 10a, and the protective sheets 22 shown in Figure 3 may be omitted. The package of Figure 8 is otherwise the same as the package of Figure 3 and need not be described in further detail, it being noted, however, that the inner bases 27 of the pallets 18a provide additional cushioning means for the article 10, further guarding against breakage or damage thereof. The articles 10 and 10a may be packaged in substantially either of the two ways shown and described by way of example, as will be understood. While I have shown the pallet decks as being of two ply or double wall construction, that is not essential and, within the broader aspects of my invention, the bases of the pallets may be of any suitable construction. Also, while the spacer blocks 20 preferably are formed of paper stock and are of hollow cylindrical construction, any suitable blocks may be used within the broader aspects of my invention. In certain cases, where the article to be packaged is unusually fragile, the spacer blocks of the pallets may be formed of chipboard or of strawboard, which is somewhat softer than cardboard or like paper stock, to provide further cushioning of the packaged article.

The pallets 18 and 18a are, for convenience, made of a standard size, the bases of the respective pallets being 60" by 72". These pallets may readily be cut, conveniently by a band saw, to desired size. In some cases, when cutting the pallet certain of the spacer blocks or posts thereof may be cut in two. That is not objectionable and the remaining portions of the cut blocks retain their efficiency as spacing and cushioning elements. When packaging large articles two or more pallets, one cut to proper size, if required, may be placed at each side of the packaged article, as will be understood. In such cases spaced cross strips may be secured to the sides of the frame, for bracing purposes and to prevent bowing inward of the sides of the frame when the steel strapping is applied. Such bracing strips are known and need not be illustrated nor further described. The cross strips, when used, cooperate with the steel strapping to restrain the pallets

against movement outward of the frame, as will be obvious. The pallets at each side of the article, though formed of two or more parts or sections, constitute, in effect, a single pallet. In the drawings the pallets have been shown as of unitary construction, for convenience of description, and by way of example only, but my invention is in no way limited to unitary pallets, as and for the reasons above pointed out. It is to be understood, therefore, that the appended claims are to be construed as inclining either unitary pallets or pallets formed of two or more sections together constituting a pallet.

As above indicated, and as will be understood by those skilled in this art, changes in details may be resorted to without departing from the field and scope of my invention, and I intend to include all such variations, as fall within the scope of the appended claims, in this application in which the preferred forms only of my invention have been disclosed.

I claim:

1. In a package for handling and shipping articles, an open sided frame, an article within said frame, and pallets secured within said frame at opposite sides of said article each comprising an outer base substantially conforming to the interior of and closing the side of said frame and spacer members extending from said outer base inward in abutting relation to said article restraining the latter against movement relative to said frame toward either side thereof.

2. In a package for handling and shipping articles, an open sided frame, an article within said frame, means closing said frame at one side thereof and abutting the adjacent side of said article providing cushioning means restraining said article against movement relative to said frame toward said one side thereof, and a pallet secured in said frame comprising an outer base substantially conforming to the interior of and closing the other side of said frame and spacer members extending from said outer base inward in abutting relation to said article restraining the latter against movement relative to said frame toward said other side thereof.

3. In a package for handling and shipping articles, an open sided frame, an article within said frame, pallets within said frame at opposite sides of said article each comprising an outer base substantially conforming to the interior of and closing the side of said frame and spacer members extending from said outer base inward in abutting relation to said article restraining the latter against movement relative to said frame toward either side thereof, and spaced resilient retaining members secured to said frame extending across the sides thereof in overlying relation to the outer bases of said pallets restraining the latter against outward movement relative to said frame.

4. In a package for handling and shipping articles, an open sided frame, an article within said frame, pallets within said frame at opposite sides of said article each comprising an outer base substantially conforming to the interior of and closing the side of said frame and spacer blocks extending from said outer base inward in abutting relation to said article, the outer base of the respective pallets being resilient while possessing substantial rigidity, and spaced retaining members secured to said frame extending across the sides thereof in overlying relation to the outer bases of said pallets.

5. In a package for handling and shipping ar-

ticles, an open sided frame, an article within said frame, pallets within said frame at opposite sides of said article each comprising an outer base substantially conforming to the interior of and closing the side of said frame and spacer blocks extending from said outer base inward in abutting relation to said article, the outer base of the respective pallets being yieldable and resilient while possessing substantial rigidity, and spaced retaining members secured to said frame extending across the sides thereof in overlying relation to the outer bases of said pallets.

6. In a package for handling and shipping articles, an open sided frame, an article within said frame, pallets within said frame at opposite sides of said article each comprising an outer base substantially conforming to the interior of and closing the side of said frame and spacer blocks secured to said base extending therefrom inward in abutting relation to said article, the outer base of the respective pallets being resilient while possessing substantial rigidity, and spaced retaining members secured to said frame extending across the sides thereof in overlying relation to the outer bases of said pallets.

7. In a package for handling and shipping articles, an open sided frame, an article within said frame, pallets within said frame at opposite sides of said article each comprising an outer base substantially conforming to the interior of and closing the side of said frame and spacer blocks extending from said outer base inward in abutting relation to said article, the outer base of the respective pallets being formed of paper stock like material, and spaced retaining bands secured to said frame extending thereabout in overlying relation to the outer bases of said pallets.

8. In a package for handling and shipping articles, an open sided frame, an article within said frame, pallets within said frame at opposite sides of said article each comprising an outer base substantially conforming to the interior of and closing the side of said frame and spacer blocks extending from said outer base inward in abutting relation to said article, the outer base of the respective pallets being formed of paper stock like material and said blocks being formed of paper stock like material and adhesively secured to said outer base, and spaced retaining bands secured to said frame extending thereabout in overlying relation to the outer bases of said pallets.

9. In a package for handling and shipping articles, an open sided frame, an article within said frame, pallets within said frame at opposite sides of said article each comprising an outer base substantially conforming to the interior of and closing the side of said frame and spacer blocks extending from said outer base inward in abutting relation to said article, the outer base of the respective pallets being formed of corrugated paper stock like material, and spaced retaining bands secured to said frame extending thereabout in overlying relation to the outer bases of said pallets.

10. In a package for handling and shipping articles, an open sided frame, an article within said frame, pallets within said frame at opposite sides of said article each comprising an outer base substantially conforming to the interior of and closing the side of said frame and spacer blocks extending from said outer base inward in abutting relation to said article, the outer base of the re-

spective pallets being formed of corrugated paper stock like material and said blocks being formed of corrugated paper stock like material and adhesively secured to said outer base, and spaced retaining bands secured to said frame extending thereabout in overlying relation to the outer bases of said pallets.

11. In a package for handling and shipping articles, an open sided frame, an article within said frame, pallets within said frame at opposite sides of said article each comprising an outer base substantially conforming to the interior of and closing the side of said frame and spacer blocks secured to said outer base extending therefrom inward in abutting relation to said article, protective sheets of material between the inner ends of the blocks of the pallets and said article, the outer base of the respective pallets being formed of corrugated paper stock, and spaced retaining bands secured to said frame extending thereabout in overlying relation to the outer bases of said pallets.

12. In a package for handling and shipping articles, an open sided frame, an article within said frame, pallets within said frame at opposite sides of said article each comprising an outer base substantially conforming to the interior of and closing the side of said frame and an inner base and spacer blocks secured between said bases disposing said inner base in abutting relation to said article, the bases of the respective pallets being formed of corrugated paper stock, and spaced retaining bands secured to said frame extending thereabout in overlying relation to the outer bases of said pallets.

13. In a package for handling and shipping articles, an open sided frame, an article within said frame, pallets within said frame at opposite sides of said article each comprising an outer base of corrugated paper stock substantially conforming to the interior of said frame and spacer blocks of corrugated paper stock adhesively secured to said base extending therefrom inward in abutting relation to said article, a corrugated paper stock liner of substantially channel cross section fitting within said frame with its side flanges and the marginal portions of the outer bases of said pallets in overlapping relation, and spaced retaining bands secured to said frame extending thereabout in overlying relation to the outer bases of said pallets.

14. In a package for handling and shipping articles, an open sided frame, an article within said frame, pallets within said frame at opposite sides of said article each comprising an outer base substantially conforming to the interior of and closing the side of said frame and an inner base and spacer blocks secured between said bases disposing said inner base in abutting relation to said article, the bases of the respective pallets being formed of corrugated paper stock, a corrugated paper stock liner of substantially channel cross section fitting within said frame with its side flanges overlapping and seating on the outer faces of the outer bases of said pallets, and spaced retaining bands secured to said frame extending thereabout in overlying relation to said flanges and the outer bases of said pallets.
